Primary Examiner — John Windmuller*Assistant Examiner* — Steven J Czyz(74) *Attorney, Agent, or Firm* — Cohen IP Law Group, PC; Michael N. Cohen(57) **CLAIM**

I claim the ornamental design for the shelving rods, as shown and described.

DESCRIPTION

FIG. 1 is a perspective view of the first rod of a shelving rods, shown separately for ease of disclosure;

FIG. 2 is a front side view thereof;

FIG. 3 is a perspective view of the second rod of the shelving rods, shown separately for ease of disclosure;

FIG. 4 is a front view thereof; and,

FIG. 5 is a perspective view of the shelving rods.

The broken lines depict portions of the article that form no part of the claimed design.
